UNITED STATES PATENT OFFICE.

ALEXANDER M. JACKSON, OF SCHENECTADY, NEW YORK, ASSIGNOR TO GENERAL ELECTRIC COMPANY, A CORPORATION OF NEW YORK.

VAPOR ELECTRIC APPARATUS.

1,074,179.

Specification of Letters Patent. Patented Sept. 30, 1913.

Application filed April 8, 1904. Serial No. 202,149.

To all whom it may concern:

Be it known that I, ALEXANDER M. JACKSON, a subject of the King of Great Britain, residing at Schenectady, in the county of 5 Schenectady and State of New York, have invented certain new and useful Improvements in Vapor Electric Apparatus, of which the following is a specification.

My present invention relates to certain 10 improvements in the starting means for vapor electric apparatus such as mercury vapor lamps, rectifiers, or the like.

In carrying my invention into practice I make use of automatic means for rotating 15 or turning the apparatus about its axis, and so construct the apparatus that the motion thus produced will operate to start the normal current flow through the same.

The points of novelty characteristic of 20 my invention are set forth with particularity in the appended claims. The invention itself, however, will be better understood by reference to the following description taken in connection with the accompanying 25 drawings, in which—

Figure 1 represents one embodiment of my invention, and Figs. 2, 3 and 4 are views of parts of the apparatus shown in Fig. 1; Fig. 5 is a view of a modified form 30 of lamp made according to my invention; and Figs. 6 and 7 are certain sectional views of Fig. 5 corresponding to different positions of the lamp tube.

In Fig. 1 the casing 1 with downwardly 35 and outwardly flared sides serves as a convenient means for supporting a mercury vapor lamp constituting one embodiment of my invention, and at the same time may operate as a reflector therefor. The lamp 40 envelop or exhausted container consists of a glass tube 2, of indefinite length, provided at some suitable point with a condensing chamber such for example as the bulb 3 opening into the tube 2. An electrode of 45 graphite or other suitable material 4 is located at one end of the tube and is connected through a suitable leading-in conductor in the usual manner with a supply-lead 5. The other electrode of the lamp consists of a 50 body of mercury 6 carried in a lateral enlargement 7 at one end of the lamp tube. Before the lamp is started the mercury occupies a position in this enlargement 7 as indicated in Fig. 3. In this position one 55 end of a filament 8 or high resistance con-

ductor dips into the mercury as shown and extends along the tube through suitable guides 9, 10 and 11 to the anode 4 to which it is electrically connected.

To provide for starting the lamp I mount 60 the tube so that it may be rotated through a convenient angle, as for example 90 degrees, whereby the mercury 6, by the action of gravity, recedes from the end of the filament 8 and thus causes a starting arc which 65 immediately puts the lamp into operation. Various means may be employed for causing rotation of the lamp. In the particular instance shown, however, the tube 2, which is represented as slightly inclined to provide 70 for the return flow of mercury, has its upper end loosely rotatable in a sort of skeleton cap or socket 12 carried by a bracket 13 fixed to the reflector 1. The lower end of the tube is cemented or otherwise secured 75 to a cap 14 carrying a projecting shaft having bearings, formed as indicated in dotted lines 15, in the bracket 16 secured to the reflector 1. This shaft is provided with a pinion 17 adapted to engage a short rack 80 18 carried by the armature or core 19 of a magnet 20. This magnet is carried by the reflector 1 and when energized draws up the core 19 and, by reason of the cooperative action of the rack and pinion, rotates the lamp in a direction to bring the condensing chamber 3 upright over the tube 2.

In the final position the mercury 6 settles in the bottom of extension 7 as indicated in Fig. 4. In moving from one position to the other, however, the end of the filament 8 breaks contact with the mercury 6. If the lamp be connected in circuit while this operation is taking place the interruption of contact thus caused produces an initial starting arc which, if the polarity be such as to make the electrode 6 negative, will give rise to an immediate starting of the main arc or current flow through the 100 length of the tube to the anode 4.

The solenoid 20 for actuating the lamp may be connected in series with the lamp as shown, or if desired may be excited in any other suitable manner.

Instead of using a lamp of the type shown in Fig. 1, I may employ various other types of apparatus, as for example that shown in Fig. 5 in which a side branch, so called, or auxiliary electrode is used for the pur- 110

pose of starting. The lamp herein shown consists of a tube 21 of indefinite length, provided at its opposite ends with shaft-carrying members 22 and 23 whereby the 5 tube may be rotatably supported. The anode of the lamp as before may consist of a graphite cylinder or shell 24 connected by a leading-in conductor with a positive supply-lead 25. At the opposite end of the 10 tube 2 pockets 26 and 27 are formed and are filled with mercury to such an extent that when the pockets occupy the position shown in Fig. 6 the mercury bridges over the space separating the pockets and form 15 an electrical connection between the two bodies of mercury.

A curved solenoid 28, with a curved core 29 secured to an arm 30 extending from the cap or member 23, operates when energized 20 to rotate the lamp tube 21. As this rotation takes place one of the pockets, as pocket 26, is raised to a higher level than the other pocket until a point is reached where the mercury connecting the two pockets finally 25 divides over the bridge or barrier 31 between the pockets. Prior to this rotation of the tube I cause current to pass from the mercury in the pocket 26 through the mercury to the pocket 27 so that when the mercury 30 separates over the bridge 31 an arc or current flow takes place through the medium of mercury vapor generated from one of the electrodes. This initial starting arc energizes one of the bodies of mercury, as for 35 example the body of mercury 32, as a cathode and has the effect of causing a second mercury arc to extend along the tube 21 to the anode 24. The starting of the arc of the tube 21 is assisted by the presence of a carbon 40 or other high resistance filament 33 extending from the anode 24 nearly the whole length of the tube but unconnected with the mercury electrode. The filament may be held in place by anchoring devices or guides 45 34 and 35.

In connecting up the lamp the positive supply main extends from 36 through a steadyng resistance 37 to the positive lead 25 of the lamp and also to a supplemental 50 positive lead 38 connected through a leading-in conductor 39 with one of the two mercury bodies or electrodes. The negative lead 40 extends from a leading-in conductor 41 connecting with the cathode or negative electrode 32 and includes in series therewith the actuating solenoid 28.

After the apparatus is started it is generally unnecessary to maintain the starting electrode in circuit, for which reason I provide a cut-out device having a coil 42 in 60 circuit with the lead 25 and operating when

actuated to break the circuit of the supplemental lead 38 at the two fixed contacts 43. This cut-out device operates automatically as soon as the main current starts in the lamp. 65

It will be obvious from the foregoing description that numerous modifications in the embodiment of my invention may be made without departing from the spirit thereof, for which reason I do not wish to be limited 70 to the exact details shown and described.

What I claim as new and desire to secure by Letters Patent of the United States, is,

1. In a vapor electric apparatus, the combination of a tubular exhausted envelop, a 75 pivotal mounting for the tube permitting it to rotate about the axis of the tube, electrodes in the tube adapted when the tube is rotated to make or break initial electrical connection with each other, and electro-magnetic means for producing a partial rotation 80 of the tube or envelop.

2. In a vapor electric apparatus, the combination of an exhausted envelop or container, a pivotal support for each end of the 85 container, an electro-magnet for turning said container on its pivots, and electrodes in said container or envelop one at least of which electrodes is fluid.

3. In a vapor electric apparatus, the combination of a pivotally mounted envelop or container, electrodes therefor one at least of which is fluid, and a filament extending from one electrode and positioned to make and break contact with the fluid electrode when 90 said apparatus turns on its pivot.

4. In a vapor electric apparatus, the combination of an envelop or container, supports for the respective ends of said container such as to permit rotation thereof, 100 electrodes in said container, one at least of which is of fluid material, a filament dipping at one end into said fluid when the container is in the starting position, and a magnet for rotating said container and thereby 105 causing separation between said filament and said fluid.

5. In a vapor electric apparatus, the combination of a pivotally mounted envelop or container, electrodes therefor, one at least of which is fluid, a filament extending from one electrode positioned to be in contact with the fluid electrode in one position of the container and means for partially rotating the container thereby withdrawing the fluid 110 electrode from contact with the filament. 115

In witness whereof, I have hereunto set my hand this 7th day of April, 1904.

ALEXANDER M. JACKSON.
